ABSTRACT OF THE DISCLOSURE

Preventing distortion or warping of the edges of a self-supporting, plexus-type heating element is accomplished by turning an edge of the plexus back upon the plexus to form a less-warpable rib.

The present invention relates to electrical heating elements and in particular to self-supporting heating elements comprising a plexus of refractory metals such as molybdenum, tantalum, rhenium, columbium and tungsten.

Refractory metal heating elements fabricated from sheet materials or machined from heavy stock are known to the art. However, the metal in a heating element of this type does not have crystal structures which resist element breakage or aid in the maintenance of element geometry.

A solution for these problems is described in United States Patent No. 3,178,665, issued on Apr. 13, 1965, to Matheson et al. In that patent are disclosed heating elements, having electrical characteristics identical to those or prior art heating elements, but whose structural characteristics are far superior to those of sheet material and machined stock heating elements.

In particular, the heating element disclosed in this patent is a foraminous plexus comprising a series of intertwined, elongated, helical convolutions of refractory metal wires. To form the plexus, a number of helically convoluted wires, each having similar electrical characteristics, are intertwined together in such a way that, generally, two convolutions are intertwined in each other convolution except for the first and last convolutions of the series, where only one convolution is intertwined.

One or more of such plexuses are assembled to fabricate a complete heating unit which satisfies the design requirements of a particular electrical furnace. The heat output of such heating unit is a direct function of the size of the plexus used.

However, because of the high temperatures prevalent in furnace operation and because of the action of electrically generated mechanical forces on the plexuses, the edges of the plexuses may be permanently warped or distorted.

It is, therefore, an object of the present invention to provide a heating element of the aforesaid type, capable of withstanding fairly large thermal shocks and electrically generated mechanical forces, without exhibiting permanent destructive physical deformation.

In accordance with the present invention, a heating element for use in an electric furnace comprises a foraminous plexus of an intertwined series of helical convolutions of refractory metal wires. The turns of each of the wires are held by the turns of an adjacent wire and at least one edge of the plexus is folded and secured to the plexus at points intermediate the edges.

Many other objects, features and advantages of this invention become manifest to those conversant with the art, upon making reference to the following detailed description of the invention taken with reference to the drawings, of which:

FIGURE 1 is a perspective view of an electrical heating unit particularly designed for use in a three-phase-powered electrical furnace; and

2

FIGURE 2 is a plan section taken through one of the heating elements or foraminous plexuses, at the section line 2—2.

One embodiment of a heating unit constructed in accordance with the present invention comprises a plurality of heating elements 10, 11, 12. Each heating element is an elongated foraminous plexus of an intertwined series of helical convolutions of refractory metal wires, for example helically convoluted wires 13 to 22. The turns of one wire, for example, turns 13a of wire 13, (one such turn being shown in FIGURE 2) are held by the turns 14a of an adjacent wire 14.

Moreover at least one of the edges 10a, 11a, 12a, 12b of each plexus 10, 11 and 12, respectively, is folded and secured to the body of the plexus at points intermediate the edges of that plexus.

In particular as shown in FIGURE 2, each plexus edge comprises a plurality of wires at the beginning (or end) of the intertwined series, for example, wires 17 to 22. The edge is folded and secured to the body of the plexus at points intermediate the edges and by means of a helically convoluted refractory metal wire 23 which engages and holds the helical convolutions in one of the wires in the aforesaid plurality, for example convolutions 22a of wire 22, and the helical convolutions 16a of a wire 16 intermediate the edges.

Use of a wire 23 having helical convolutions 23a makes the fabrication of a heating element 10, 11, 12 very simple, since the wire 23 may be turned, as a screw, into the convolutions 16a and 22a of wires 16, 22. However, other means for securing the folded edges of the plexus to points intermediate the edges, such as for example, wires having nonhelical convolutions or single wire loops used at the top, bottom and/or midpoints of the folded edges, should be readily apparent to those skilled in the art.

The heating elements 10, 11, 12 may be assembled in a cylindrically shaped unit by fastening their lower ends to a cylindrical conducting ring 24. The other ends of plexuses 10, 11, 12 are fastened and insulated from each other by means of conducting arms 25, 26, 27 for connecting each plexus to a power supply, for example, a source of three phase electrical power. In making such electrical connections cylindrical ring 24 serves as a common node.

In the preferred embodiment of the aforesaid heating unit, the refractory metal used is tungsten. By folding at least one of the edges of each plexus away from the edges of adjacent plexuses, the interaction of electrically generated mechanical forces on the plexuses is minimized at those places where such forces in prior art heating units tended to do most damage, that is, the adjacent edges.

Furthermore, this minimization of destructive mechanical forces is accomplished without decreasing the heating capacity of the plexus.

While there is shown and described herein certain specific structure embodying the invention, it will be manifest to those skilled in the art that various modifications and rearrangements of parts may be made without departing from the spirit and scope of the underlying inventive concept and further that this concept is not limited to the particular forms herein shown and described, except insofar as indicated by the scope of the appended claims.

As our invention we claim:

1. A heating element for use in an electric furnace comprising: an elongated foraminous plexus of an intertwined series of helical convolutions of refractory metal wires, the turns of one of said wires being held by the turns of an adjacent wire, at least one of the edges of said plexus being folded and connected to the body of said

plexus, the fold being connected to said plexus at points intermediate the edges.

2. The heating element according to claim 1, in which each of said edges comprises a plurality of said wires at the beginning and at the end, respectively, of said intertwined series.

3. The heating element according to claim 2 in which at least one of said edges is secured to said plexus by helically convoluted, refractory-metal wire means for holding the helical convolutions of one of said plurality of wires and the helical convolutions of one of said wires intermediate said edges.

4. An electrical heating unit comprising: an elongated plexus of an intertwined series of helical convolutions of refractory metal wires, the turns of one of said wires being held by the turns of an adjacent wire, at least one of the edges of said plexus being folded and connected to the body of said plexus, the fold being connected at points intermediate said edges; and means for connecting said plexus to a power supply.

5. The electrical heating unit according to claim 4 in which each of said edges of said plexus comprises a plurality of said wires at the beginning and at the end, respectively, of said intertwined series.

6. The electrical heating unit according to claim 5 in which at least one of said edges is secured to said plexus by helically convoluted, refractory-metal wire means for holding the helical convolutions of one of said plurality of wires and the helical convolutions of one of said wires intermediate said edges.

7. An electrical heating unit comprising: a plurality of

heating elements, each of which is an elongated foraminous plexus of an intertwined series of helical convolutions of refractory metal wires, the turns of one of said wires being held by the turns of an adjacent wire, at least one of the edges of said plexus being folded and connected to the body of said plexus, the fold being connected to said plexus at points intermediate said edges; and means for connecting said heating elements to a power supply.

8. The electrical heating unit according to claim 7 in which each of said edges of said plexus comprises a plurality of said wires at the beginning and at the end, respectively, of said intertwined series.

9. The electrical heating unit according to claim 8 in which at least one of said edges is secured to said plexus by helically convoluted, refractory-metal wire means for holding the helical convolutions of one of said plurality of wires and the helical convolutions of one of said wires intermediate said edges.
